Filed Feb. 28, 1968, Ser. No. 10,777

Term of patent 14 years

Int. Cl. D21—03

U.S. Cl. D34—5

FIG. 1.

FIG. 2.

FIG. 3.

FIG. 4.

FIG. 1 is a front elevation view of a tennis racket frame embodying our ornamental design;

FIG. 2 is a side elevation view of the tennis racket frame of FIG. 1;

FIG. 3 is a top view of the tennis racket frame of FIG. 1; and

FIG. 4 is a bottom view of the tennis racket frame of FIG. 1.

The characteristic feature of our design resides in the configuration on the tennis racket frame disclosed of the spaced apart tubular members forming the head, which are connected by pins giving a ladder-like effect thereto, together with an arcuate piece at the throat, all as shown.

We claim:

The ornamental design for a tennis racket frame, as shown and described.
